(57) **CLAIM**

The ornamental design for a computer, as shown and described.

DESCRIPTION

FIG. 1 is a front, top, right perspective view of a computer showing my new design; and

FIG. 2 is a top elevational view thereof; and,

FIG. 3 is an enlarged perspective view thereof along the lines 3-3 and 3'-3' of FIG. 1, wherein the portions that emit light of desired color when electric power is on are shown in gray.

1 Claim, 3 Drawing Sheets

FIG. 1

FIG.2

FIG.3
